UNITED STATES PATENT OFFICE.

ALFRED HEALD, OF PHILADELPHIA, PENNSYLVANIA, ASSIGNOR TO
McCALLUM, CREASE & SLOAN, OF SAME PLACE.

DESIGN FOR A CARPET-PATTERN.

Specification forming part of Design No. 5,879, dated May 28, 1872.

Specification describing a Design for a Carpet-Pattern, produced or invented by ALFRED HEALD, of Philadelphia, Pennsylvania.

Design for a Carpet-Pattern.

My design for a carpet-pattern is fully represented in the accompanying drawing; and consists mainly of figures A and B, of a dark shade or color, arranged upon a light ground-work, D; or the ground may be dark and the figures light. The figures A are square or diamond-shaped, and are comparatively plain, but the figures B are of an elaborate design, as clearly represented in the drawing, and have a broken outline composed of angles and curves. In the center of the ground-work D is a cruciform ornament, a, surrounded by trefoils b and b', and directly opposite the trefoils b are ornamented arms d, which extend quite to the center of the figures A. The ornament

a, trefoils b, and arms d are on a line parallel with one side of the figure B, and as the same arrangement is repeated on all four sides of each of the said figures it has the effect of an extended border entirely inclosing the same. In addition to the above features the ground-work of the carpet is also ornamented by sprigs and leaves e, arranged in the form of scrolls.

Irrespective of the colors employed, I claim—

The design for a carpet-pattern substantially as described, and as illustrated in and by the accompanying drawing.

In testimony whereof I have signed my name to this specification in the presence of two subscribing witnesses.

ALFRED HEALD.
